(57) **CLAIM**

The ornamental design for a golf club head, as shown and described.

DESCRIPTION

FIG. 1 is a perspective front view of a golf club head;
FIG. 2 is a front elevation view of the golf club head;
FIG. 3 is a rear elevation view of the golf club head;
FIG. 4 is a left elevation view of the golf club head, right elevation view is a mirror image thereof;
FIG. 5 is a top plan view of the golf club head; and,
FIG. 6 is a bottom plan view of the golf club head.
The broken line showing of the shaft and handle on FIG. 1 is for illustrative purposes only and forms no part of the claimed design.
